UNITED STATES PATENT OFFICE

2,476,792

ELECTRICALLY CONTROLLED SAFETY GATE

Frank Richard Allen, Roxbury, Mass.

Application November 22, 1946, Serial No. 711,542

8 Claims. (Cl. 160—7)

1

The present invention relates generally to protective or safety devices and appliances for safes, stores, banks, show-windows and similar structures and places, and more specifically to an improved electrically controlled safety gate of the lazytongs or toggle-jointed type, which is designed as a barrier, guard, or shield, against robbery.

For convenience in illustration and description the automatically operated gate is shown as controlled by a circuit mounted upon a store window, or glass plate that is frangible; and in carrying out my invention I employ an extensible and retractile gate in the form of a barrier that is automatically movable in a vertical plane, from beneath the floor of a structure, such as a store or bank that is to be protected, to an elevated or extended protective position above the floor and in front of the articles to be protected.

An electrically operated safety system is provided for automatically breaking a control circuit; or multiple pedal-controlled switches may selectively be used, for energizing electrically operated releasing means to permit automatic extension of the barrier. Electrically controlled mechanism is utilized for supporting the barrier in elevated or operative position; and electrically controlled power mechanism is employed for depressing the elevated barrier to its initial, inoperative position beneath a floor.

The primary object of the invention is the provision of a protective appliance of this type that is composed of a minimum number of component parts that may with facility be manufactured at low cost of production, and which may be assembled, installed, or erected with convenience, to insure a reliable, durable and effective system of protection for the purpose specified.

The invention consists in certain novel features of construction and combinations and arrangements of parts as will hereinafter be described, and more specifically defined and set forth in the appended claims.

In the accompanying drawings I have illustrated one complete example of a physical embodiment of my invention wherein the parts are combined and arranged in accord with one mode I have devised for the practical application of the principles of my invention. It will, however, be understood that changes and alterations are contemplated and may be made in these exemplifying drawings and mechanical structures, within the scope of my claims, without departing from the principles of my invention.

Figure 1 is a view in elevation showing an in-

2

stallation of the protective system of my invention, with the extensible gate depressed and retained in inoperative position, and disclosing diagrammatically an electrical release system under control of a circuit breaking switch for a store window, show window, or similar breakable plate.

Figure 2 is an enlarged view in elevation of the depressed barrier with its electrically controlled release circuits, actuating or elevating springs; and electrically controlled mechanism for depressing the gate or barrier.

Figure 3 is a view similar to Fig. 2 with the barrier elevated to operative position.

Figure 4 is a transverse vertical sectional view of the equipment, with the gate in elevated position, and illustrating the use of a bullet-proof glass plate carried by the gate or barrier.

Figure 5 is a longitudinal sectional view through the lower or base bar of the extensible gate, disclosing the loose pivotal connections of the toggle joints or lazy tongs.

Figure 6 is a front view of the base bar in Fig. 5.

Figure 7 and Figure 8, are detail views of one of the elevating rack bars with a resiliently mounted switch plate.

Figure 9 is a detail view in elevation at the top of the retracted or depressed barrier.

Figure 10 is a detail edge view or end view as seen in Fig. 9.

Figure 11 is an enlarged detail vertical sectional view of one of the two detaining or locking bolts.

Figure 12 is a horizontal sectional view of the bolt casing with its bolt mounted therein.

Figure 13 is a detail view at one end of one of the supporting bolts which support the barrier in elevated position; and

Figure 14 is a diagrammatic view of the electrical control system for the two detaining or locking bolts and the pair of gate-supporting bolts.

In order that the equipment and installation may readily be understood I have indicated in Fig. 4 a floor F having a vertical passage therethrough, and a counter C of conventional type is shown by dotted lines, together with the barrier or gate having a bullet-proof glass plate P mounted on and carried by the extensible gate in suitable manner as an additional protective means for valuables against robbery.

As best seen in the elevated or extended position of Fig. 3, the barrier or gate includes a lazy tong or toggle jointed structure I of metal or other suitable material and of desired size, which

is equipped with an upper movable cross bar 2 and a lower stationary bottom bar or base bar 3, that provide a rectangular structure which may be projected and retracted with relation to the stationary base bar. The cross bars are preferably of channel shape and provided with slotted, centrally located guide tongues 4, 4, and the pivot joints of the lazy tong structure are arranged to permit quick action and movement in extending and in depressing the barrier, as it is automatically elevated, and depressed mechanically by power operated means, with relation to the floor F.

The lower end of the barrier, beneath the floor, is provided with two spaced stationary frames 5 and 6 that are bolted or otherwise secured to and depend from the base bar 3, and these frames are each provided with a lateral projection or support 7, 7 which co-act with bolts 8 and 9 in supporting the barrier or gate in elevated or extended position.

For elevating or raising the barrier from its initial depressed position beneath the floor, a pair of upright spaced bars 10 and 11 are united by a horizontal tie bar 12 that is loosely pivoted to the barrier 1, as at 13, 13, above the base bar 3, and these elevating bars, which move with the gate structure are of sufficient length to telescope through suitable guide blocks or bases 14, 14 that are mounted at the line of a sub-floor indicated as S of a building structure.

Structurally heavy and comparatively strong helical springs 15, 15 are coiled about the elevating bars 10, 11 and interposed between the supports 7, 7, and a pair of anchors for the lower ends of the springs, as for instance, the two bases 14, 14; and a pair of detaining slide bolts 16 and 17 are employed for co-action with the springs in locking the barrier in depressed position.

The barrier is automatically elevated by the springs when the detaining bolts are retracted or withdrawn; the supporting bolts 8 and 9, under electric control, are projected to position for co-action with the supports 7, 7, of the elevating bars after the barrier is elevated; and after the barrier has served its purpose, the elevated structure is depressed to initial and inoperative position.

For use in retracting and depressing the barrier, a centrally located, upright rack bar 18 is rigidly bolted to the frame bar 12, and this rack bar rides against an anti-friction roller 19 journaled upon the base bar 3. The vertically movable bar is elevated by means of a rack gear 20 meshing with the teeth of the rack bar and keyed upon a horizontal rotary shaft 21, which is journaled in bearings 22 that are mounted upon a fixed frame 23, 23; and an electric motor 24 provides the power for actuating the rack and gear for lowering the barrier, it being understood that the gear rotates idly as the rack bar is elevated with the barrier.

The two supporting bolts 8 and 9, and the two locking bolts 16 and 17, are each mounted to slide and reciprocate horizontally in a housing as 25, which is supported or suspended in proper position with relation to the elevating bars, on stationary frames 26 rigid with the frame members 5 and 6, and each of the bolts, which are equipped with anti-friction rollers 27, is projected by means of a spring 28, and retracted by means of electrically operated appliances.

With the supporting bolts 8 and 9 retracted, and the detaining bolts 16 and 17 projected into locking position for co-action with the springs 15,

as indicated in Fig. 1 where a store window W is equipped with an electric control circuit 29 preferably made up of tinfoil and including a battery B; if the window glass is broken and the circuit 29 thus interrupted, a relay 30 is closed to energize the operating circuit 31 for the two bolts 16 and 17. The operating circuit includes solenoids 32, 32, and when energized, these solenoids utilizing the rear ends of the bolts as armatures, retract the bolts from locked position thus permitting the springs to project the barrier to uplifted position. In lieu of the broken window pane W, multiple, pedal-operated switches may selectively be used in the control circuit 29 for energizing the operating circuit 31 of the bolts 16 and 17 to unlock these bolts.

Immediately following the elevating movement of the barrier the supporting bolts 8 and 9, that have been held in retracted position by means 20 of solenoids 33, 33 which are included in normally closed circuit 34 connected with power lines 35 and 36, are released as by a circuit breaker 37. As the solenoids 33, 33, are de-energized, the spring-pressed bolts 8 and 9 are projected into position beneath the supports or abutments 7, 7, of the elevating bars 10—11, to rigidly support the extended or elevated barrier in upright position.

The electric motor 24 and the rack 18 and gear 20 are utilized in resetting the appliance by reTRACTING the barrier and depressing it below the floor, after the operating circuit 34 has been closed to energize the solenoids 33 and the supporting bolts thus retracted from the abutments 7.

If necessary or desirable, the barrier may also 35 be elevated by power from the motor through the rack and gear, and for this purpose a bevel-gear clutch 37 is interposed between the motor shaft and the gear shaft 21 and operated by a solenoid 38 which is included in the circuit 31 of the locking bolts 16 and 17.

When the motor circuit 35—36 is closed and the motor 24 is operated to revolve the gear 20, the rack bar is depressed carrying with it the folding portion of the elevated barrier, and the depression of the barrier is automatically stopped as a movable contact 39 mounted on the rack bar frictionally engages and operates or opens a relay 40 in the circuit 31. At the same time the retracted locking bolts 16 and 17 are released by their solenoids 33 and their springs project these bolts into detaining position over the springs 10, 11, to lock the barrier in depressed position, thus setting the appliance in position for automatic action when required.

Various electrical appliances such as relays and other necessary equipment including switches are provided for proper control of the control and operating circuits, and changes and alterations may be made in the illustrated diagrams in adapting the appliance to various protective purposes. The barrier may be manufactured in different sizes for different purposes, and more than one barrier may be installed and equipped with the electrically controlled operating mechanism of my invention for use in protection of valuables in stores, banks, and other places.

Danger signals of the audible type, or of the visual type, may be included in the electrical system, for automatic operation, and other appliances may be utilized in the installation of the protective system.

Having thus fully described my invention, what I claim as new and desire to secure by 75 Letters Patent is:

1. In an electrically controlled protective appliance, the combination with a depressed automatically elevatable gate having supports, of spring-bolts for locking the gate in depressed position and electrically controlled means for releasing the bolts, electrically retracted and spring-pressed bolts for co-action with the supports for holding the gate in elevated position, mechanical means for depressing the barrier, and electrical controls for said mechanical means.

2. In a protective appliance, the combination with a depressed and extensible gate of the lazy tongs type having movable supports, of spring-pressed slide bolts for detaining the gate in depressed position and electrically controlled means for releasing the bolts, automatic means for elevating the depressed gate, spring pressed slide bolts for supporting the elevated gate, and electrically operated means for retracting the supporting bolts.

3. In a protective appliance, the combination with a depressed lazy tongs gate having movable supports, and automatic means for extending the gate, of spring-pressed bolts engaging the supports and means for releasing said bolts, a second pair of spring-pressed bolts adapted to support the gate in elevated position and means for releasing said bolts, and means for depressing the elevated gate.

4. In a protective appliance, the combination with a depressed lazy tongs gate having movable supports, and resilient automatic means for extending the gate, of locking means engaging said supports to hold the gate in depressed position and means for unlocking said means, means adapted to coact with the supports for supporting the gate in elevated position and means for releasing this supporting means, and means for depressing the elevated gate.

5. In a protective appliance, the combination with a lazy tong gate having movable supports, and spring-actuated means for elevating the gate from depressed position, of spring-pressed slide bolts for detaining the spring actuated means in depressed position and electrically operated means for releasing said bolts, spring-pressed supporting bolts for holding the gate in elevated position and electrically operated means for releasing these bolts, mechanical means for depressing the gate, and electrically controlled means for operating the mechanical means.

6. In a protective appliance, the combination with a depressed lazy tongs gate having a pair of elevating bars, supports on the bars, and springs for elevating the bars, of spring-pressed slide bolts for coaction with the supports in detaining the gate in depressed position and means for retracting said bolts, spring-pressed bolts for coaction with the supports in elevated position and means for depressing the gate.

7. In a protective appliance, the combination with a depressed lazy tongs gate having a pair of spaced elevating bars, supports on the bars, a central rack bar rigid with the elevating bars, a rack gear coacting with the rack bar and means for rotating the gear to depress the gate, of springs for coaction with the supports in elevating the gate, detaining means coacting with the supports for holding the gate in depressed position and means for releasing the detaining means, retracted supporting means, and means for projecting said means into coaction with the elevated supports.

8. In a protective appliance, the combination with a depressed lazy tong gate having a pair of elevating bars and supports thereon, an intermediate rack bar rigid with the bars, a rack gear coacting with the rack bar for depressing the gate, and electrically controlled means for rotating the rack gear, of springs mounted on the elevating bars for coaction with the supports in elevating the gate, spring-pressed slide bolts detaining the gate in depressed position and electrically operated means for retracting the bolts, spring-pressed slide bolts adapted to coact with the supports in elevated position for supporting the elevated gate, and electrically controlled means for retracting the last mentioned slide bolts.
